Primary Examiner — Antoine D Davis(74) *Attorney, Agent, or Firm* — Coats & Bennett, P.L.L.C.(57) **CLAIM**

The ornamental design for a tape measure housing, as shown and described.

DESCRIPTION

FIG. 1 is a front perspective view of a tape measure housing showing my design.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

The broken lines are environmental only and form no part of the claimed design.
